(57) **CLAIM**

The ornamental design for a cap, as shown and described.

DESCRIPTION

FIG. 1 is an angled top perspective view of a variation of a cap;

FIG. 2 is a side view of the variation of the cap shown in FIG. 1;

FIG. 3 is a top view of the variation of the cap shown in FIG. 1;

FIG. 4 is a bottom view of the variation of the cap shown in FIG. 1;

FIG. 5 is an angled top perspective view of a variation of a cap;

FIG. 6 is a side view of the variation of the cap shown in FIG. 5;

FIG. 7 is a top view of the variation of the cap shown in FIG. 5; and,

FIG. 8 is a bottom view of the variation of the cap shown in FIG. 5.

The broken lines are shown for the purpose of illustrating portions of the cap that form no part of the claimed design.

1 Claim, 8 Drawing Sheets
